Patented Mar. 25, 1975

234,562

TESTING FRAME FOR BREATHING AND RESCUE APPARATUS

Robert Donkin, Rotherham, England, assignor to Coal
Industry (Patents) Limited, London, England

Filed Mar. 22, 1973, Ser. No. 343,951

Term of patent 14 years

Int. Cl. D6—04

U.S. Cl. D6—186

FIG. 2.

FIG. 3.

FIG. 4.

FIG. 5.

FIG. 1 is a front, top and right side perspective view of a testing frame for breathing and rescue apparatus showing my new design;

FIG. 2 is a top plan view;

FIG. 3 is a right side elevational view;

FIG. 4 is a front elevational view; and

FIG. 5 is a rear elevational view.

I claim:

The ornamental design for a testing frame for breathing and rescue apparatus, as shown.
